UNITED STATES PATENT OFFICE.

CLINTON S. MARSHALL, OF WORCESTER, MASSACHUSETTS, ASSIGNOR TO
AMERICAN STEEL & WIRE COMPANY OF NEW JERSEY, OF WORCESTER,
MASSACHUSETTS, A CORPORATION OF NEW JERSEY.

CUTTING MECHANISM FOR WIRE-FABRIC MACHINES.

No. 806,420.

Specification of Letters Patent.

Patented Dec. 5, 1905.

Application filed March 17, 1905; Serial No. 250,603.

To all whom it may concern:

Be it known that I, CLINTON S. MARSHALL, a citizen of the United States, residing in the city and county of Worcester, State of Massachusetts, have invented certain new and useful Improvements in Cutting Mechanism for Wire-Fabric Machines; and I do hereby declare the following to be a full, clear, and exact description of the invention, such as will 10 enable others skilled in the art to which it appertains to make and use the same.

The invention relates in general to the machine originally covered in the patents to A. J. Bates, February 23, 1897, No. 577,639, and 15 October 19, 1897, No. 591,996, certain improvements on which were patented to said Bates and J. A. Cocker, jointly, June 30, 1903, No. 732,155; and the present invention relates specifically to that part of the machine 20 covered by the Bates and Cocker patent where a drum is employed with vertically-reciprocating crimping-bars which grip the longitudinal wires and pull the fencing through the machine, passing it on to the drum, on which 25 it is wound ready for the market.

The object of the invention is to provide for automatically and simultaneously cutting all the longitudinal wires, thus saving the time and labor required to cut them separately by 30 hand, as has heretofore been necessary whenever it was desired to separate the fencing already wound on the winding-drum from that passing through the machine.

In order to effect the above object, I provide the feeding-drum of the before-mentioned Bates and Cocker patent with a knife bar or bars sliding vertically in grooves in the shell of the drum alongside of the stationary plates of the crimping mechanism, and I 35 provide for operating this knife or knives automatically by simply throwing into the path of the lower projecting end thereof a cam-roller, so that as the feeding-drum revolves the knife is operated by the roller and the 40 whole line of wires carried by the drum is severed at one operation. The knife-bar is notched to receive each strand-wire, and the 45 notches correspond in number and position with those in the crimping-bar and plates carried by the drum. Normally the notches in the knife-bar register with those in the stationary crimping-plates; but when the cam- 50 roller engages the lower end of the bar it

slides it upward and shears off the wires which lie in the grooves of the plates and bar. The 55 fencing passes through the machine in the same way as described in the former patent to Bates and Cocker, and all the strand-wires are gripped by the crimping-bars of the feeding-drum at the same period as in the patent, 60 so as to pull the fencing through the machine and pass it on to the winding-drum. The present invention is concerned, however, only with the cutting of the strand-wires, and so far as the crimping of the wires and the pulling 65 of the fence are concerned the construction is or may be the same as in the former patent.

The present improvement is illustrated in the accompanying drawings, wherein—

Figure 1 is a horizontal section through the 70 rear end of the machine, showing the crimping and feeding drum and other parts. Figs. 2 and 3 are elevations of this drum looking in the direction of the arrows *x y*, respectively, on Fig. 1. Fig. 4 is an enlarged cross-section of the feeding-drum, showing also the knife-bars and the means for operating them. Fig. 5 is a detail showing in elevation the knife-bar-operating cam-roller and other mechanism. 75

Referring to the views, *a* in Fig. 1 is the winding-drum on which the completed fence is wound ready for the market. The feeding-drum is indicated at *b*. It is or may be constructed precisely as in the Bates and Cocker 85 patent, with stationary crimping-bars *c* seated in longitudinal grooves in the shell of the drum at suitable intervals apart. These bars are arranged in pairs, as shown, and between them slide similar bars *d*, that are provided 90 with notches corresponding in shape and position with those in the stationary bars. The movable bars project beyond the heads of the drum at both ends and carry each a small roller *e* at the lower end, which rides on a 95 cam-track *f*, which is inclined, so that as the roller travels over its upper surface each movable crimping-bar is given a sufficient longitudinal movement between the stationary bars to grip the strand-wires and enable the drum 100 to pull the fencing through the machine and so, also, as to put an additional crimp in these wires.

The present invention is not limited to any particular number of cutters; but as here 105 shown the crimping-roller is provided with

two cutters at diametrically opposite points. As best shown in Figs. 2 and 4, at these points one of the stationary crimper-plates d' is made larger than the other, and in addition to its 5 function in coöperation with the movable crimper to grip the wires it also acts as the stationary member of the cutting mechanism against which slides the movable knife-bar g , before referred to. This bar g also projects 10 below the head of the drum and has at its lower end a shoe h , and on the base-plate of the machine at any suitable point, but preferably inside of the frame or plate on which the cam-track f is mounted, a cam-roller i is 15 located in such position from the center of the drum that as the latter revolves the shoe will strike the roller when the latter is thrown into operative position and cause the movable knife-bar to be operated, shearing off all the 20 longitudinal wires simultaneously and making a clean cut clear across the fencing.

The cam-roller i is mounted in one arm of a bell-crank lever k , that is pivoted at its angle in a stand or bracket l , bolted to the base-plate of the machine, so that when the lever 25 is rocked the roller is thrown into and out of position to engage the shoe h on the end of the knife-bar. The normal position of the cam-roller is shown in dotted lines in Fig. 5, 30 in which position it is held by the tension of a spring m , that is connected at its upper end to a standard n and has its lower end fastened to a bar o , one end of which is pivoted to the bell-crank lever and the other end of which 35 passes loosely through a perforation or bearing p , rising from the base-plate of the machine. As best shown in Fig. 1, this mechanism for operating the knife-bar is preferably located inside of and near the end of the 40 cam-track f , which operates the crimper-bars, so that the parts are in convenient position for the operator and so, also, that the crimper-bars will release the strand-wires at or immediately after they are cut. The cam-roller 45 being normally in the position indicated in dotted lines in Fig. 5 and the operator seeing that sufficient fencing is wound upon the winding-drum a and desiring to cut off the wound roll without discontinuing the operation 50 of the machine simply presses his foot upon the lever o and depresses it against the tension of the spring m until the bell-crank lever brings the cam-roller i into the position shown in full lines in Fig. 5, in which position 55 the shoe h of the knife-bar g , traveling in the direction of the arrow in Fig. 5, will strike the roller and cause the bar to slide in its groove in the feeding-drum sufficiently to shear off all the longitudinal wires between 60 the edge of said bar and the edge of the corresponding fixed bar d' . There may be as many of these knife-bars as desired. It will be found, however, that two are sufficient, and one may be all that is necessary.

65 Any suitable means may be employed for

returning the knife-bar to position after having been actuated by the cam-roller. In Fig. 2 I show the same means which is illustrated and described in the Bates and Cocker patent for returning the movable crimper-bars—viz., 70 a roller v positioned so as to engage the upper ends of the bars and depress them—the roller in the present improvement acting also on the upper end of the knife-bar to return it to the normal position, with its notches t registering with the notches s in the crimper-bars, as shown in Fig. 3, so that the wires are received in the notches of said crimper and knife bars in precisely the same way that they are received in the bars of the feeding-drum 80 of the former patent.

It is to be noted in respect of the above-described improvement that the operation of cutting the wires is entirely distinct and separate from that of the crimping-bars and that 85 the cutter may be employed or not, as desired, and that when employed it may be thrown into action whenever desired and immediately resumes its normal position after the shoe of the knife-bar has passed off the cam-roller. 90

Having thus described my invention, what I claim, and desire to secure by Letters Patent, is—

1. In a machine for making wire fencing having a plurality of strand-wires, the combination of a rotary drum, a knife-bar carried thereby for severing all the wires simultaneously, and means independent of the drum for operating the knife-bar, said means being normally out of action but adapted to be thrown 95 into operative position by the operator whenever desired.

2. In a machine for making wire fencing having a plurality of strand-wires, the combination of a drum having means for gripping 105 the wires and pulling the fencing through the machine, a knife-bar carried by the drum for severing all the wires simultaneously, and a cam-roller independent of the drum for operating the knife-bar, said roller being normally 110 inoperative but adapted to be thrown into operative position by the operator.

3. In a machine for making wire fencing having a plurality of strand-wires, the combination of a drum having means for crimping 115 the wires and pulling the fencing through the machine, a knife-bar carried by the drum for severing all the wires simultaneously, a shoe or projection on one end of the bar, a bell-crank lever pivoted independently of the drum, a cam-roller carried by one arm of the lever in position to be engaged by the shoe of the knife-bar as the drum rotates, means connected to the other arm of the lever for holding 120 the cam-roller normally out of operative position, and means under control of the operator to throw the roller into the path of the knife-bar shoe when it is desired to cut the fencing.

4. In a machine for making wire fencing 125

having a plurality of strand-wires, the combination of a drum having means for gripping and pulling the fencing through the machine, a knife-bar carried by the drum for severing all the wires simultaneously, a shoe or projection on the end of the knife-bar extending below the drumhead, a bell-crank lever pivoted under the drumhead and carrying a cam-roller on one arm, a spring connected to the other 10 arm of the lever for holding the cam-roller in a normally depressed position, and a foot-

piece connected to the lever by means of which the operator may rock the lever against the spring and lift the cam-roller into position to be struck by the knife-bar shoe to operate the 15 knife as the drum revolves.

In testimony whereof I affix my signature in presence of two witnesses.

CLINTON S. MARSHALL.
